UNITED STATES PATENT OFFICE.

ALBERT T. VAN ALSTYN, OF NEW YORK, N. Y.

CLASP.

1,245,070.

Specification of Letters Patent.

Patented Oct. 30, 1917.

Application filed June 10, 1911. Serial No. 632,336.

To all whom it may concern:

Be it known that I, ALBERT T. VAN ALSTYN, a resident of New York, in the county of New York and State of New York, have invented certain new and useful Improvements in Clasps, of which the following is a specification.

This invention relates to clasps; more particularly to that class of clasps which are used in connection with garters and the like but which may have a more general application for other similar purposes. The principal object of the invention is to provide a device of this class which shall hold the fabric firmly without danger of injuring the same and which may be positively and securely locked in engaging position.

For the attainment of these ends and the accomplishment of other new and useful objects, as will appear, my invention consists in the features of novelty in the construction, combination and arrangement of the several parts generally shown in the accompanying drawing and described in the specification but more particularly pointed out in the appended claims.

In the accompanying drawing, Figure 1 is a front view of a preferred embodiment of my invention in open or unengaged position.

Fig. 2 is a sectional view of the same on line 2-2, Fig. 1.

Fig. 3 is a view of the buckle in closed position engaging a fabric.

35. Fig. 4 is a cross sectional view on the line 4-4, Fig. 3.

Fig. 5 is a detail perspective view of the apertured member.

Fig. 6 is a detail view of the pivoted plate which is movable in the apertured member.

Fig. 7 is a detail view of the clamping lever.

Fig. 8 is a detail view of the member which is inserted through the apertured member. The figure will show a detail view of the member.

The difficulty with devices of this class heretofore has been that in binding fabrics of a delicate nature they are easily torn if securely held and if not securely held 50 they slip easily out of engagement with the buckle. This invention is adapted to obviate this difficulty by presenting a large surface for engaging the fabric and a positive means for operating the engaging means 55 and locking the fabric securely in position.

An apertured member 10 is formed of any

suitable plain material such as thin metal and the like, the aperture 11 being preferably rectangular in form. The edges of the member are folded inwardly and form a guideway 12 at the sides of the aperture. One end of the member 10 is bent to form the loop 13 and a resilient clip 14 which extends below the aperture 11. The other end of the member 10 is bent over at 15 to form a smooth bearing surface and to present a smooth end 16 which does not catch the fabric. Projecting lugs 17 provided with the apertures 18 are bent from the side of the member 10 which is opposite the clip 14, the opening being adapted to mount the lever 19 by means of its projections 20. A plate 21 having projections 22 at one end is adapted to be pivotally mounted in the guideways 12 and to be movable longitudinally therein. At the other end of this plate 21 are projections 23. The lever 19 is provided with perforated lugs 24 bent from the face of the plate and adapted to receive the projections 23 of the plate 21. It will be seen by reference to Figs. 2 and 3 that the position of the plate 21 is governed by the position of the lever 19. This lever 19 is formed at one end with a bent portion 25 and the tongue thus formed by the bent portion provides a stop adapted to engage the plate 21 when the latter is drawn out of engaging position as shown by Fig. 2.

A member 26 is formed of a single piece of metal, rubber, or other suitable material and is provided at the ends with openings 27, the portion intermediate of the ends being reduced in width and folded upon itself to form a rounded tip 28 substantially parallel with the ends and separated therefrom by a neck portion 29. This neck portion 29 is preferably covered with some suitable resilient material 30 such as rubber or the like. The tip 28 is adapted to be inserted through the aperture 11 of the member 10, the ends, however, being substantially the same width as the apertured member so that the member 26 is retained on one side of the member 10. When the tip 28 is inserted through the aperture 11 the plate 21 may be moved into engaging position with respect to the tip 28 by the movement of the lever 19. In engaging a fabric A the material is placed over the tip 28 and pressed through the apertured member 10 and the plate 21 is moved into engaging position against the neck portion 29 of

the member 26 thereby engaging the material which surrounds the tip and pressing the material and the tip in engagement with the edge 15 of the apertured member. It 5 will be seen by reference to Fig. 3 that the lever 19 is rotated about its axis until the end 25 engages the clip 14 which forces the other end in engagement with the tip 28 thereby protecting the fabric on the tip 10 and assisting in holding the fabric in engagement with the buckle. When the plate 21 and the lever 19 are in engaging position the point of engagement between the lever and the plate falls without the line of engagement as defined by the end of the plate 15 and the pivotal mounting of the lever so that the plate 21 is held positively in engaging position whether the lever 19 is engaged by the resilient clip 14 or not. It 20 is preferable, however, to employ the clip 14 as shown.

These clasps are commonly located at the end of a flexible band and in such connection there is provided a double looped link 25 31, to one bar of which the loop 13 of the apertured member 10 is secured, which allows the member 10 to swing freely about the bar. The member 26 is supported from the central bar of the link by means of a 30 flexible band 32 which passes through the apertures 27 and assists in securing the ends of the said member together. This flexible connection 32 permits the member 26 to be readily placed in position with respect to 35 the apertured member 10 and to be rapidly and easily withdrawn therefrom. The other bar of the link may be wider than the bar to which the member 10 is secured, as shown by Fig. 1 to provide a wider surface for 40 the engagement of a flexible band or fabric 33. While this clasp is particularly adapted for use in connection with garters and the like, it is evident that it may have a more general application and that it is adapted 45 for use in any place where it is desired to clamp a fabric for the reason that the tip 28 provides a large surface for the fabric to be engaged and the engaging means is adapted to securely lock the fabric in connection with the clasp.

I desire not to be limited to the exact construction, combination and arrangement of the several parts as herein described, for it is evident that those familiar with the art 55 to which this appertains may make various changes without departing from the spirit and scope of the invention.

What is claimed as new is:—

1. In a clasp of the class described, the 60 combination with an apertured member, the sides of which are turned inwardly to form parallel guideways of a second member having a tip which is adapted to be inserted through said aperture, a plate having side 65 projecting lugs at one end thereof which

engage in the said guideways, the plate being slidable on said lugs in the guideways, and a lever pivoted in the apertured member having a pivotal connection with the other end of the said plate whereby the latter is moved and locked in position against the tip in the guideway, and having one end of the lever bent so that when the plate is drawn out of locked engagement the bent end of the lever will engage the 75 plate and hold the lever away from the apertured member.

2. In a clasp of the class described, the combination with an apertured member having guideways along the sides thereof, of a second member having a tip adapted to be inserted in the aperture, a plate pivotally mounted about one end and movable in the guideways, a lever pivoted on one side of the apertured member and having pivotal 80 connection with the other end of the said plate, the lever being operative to move the plate in the guideways whereby the tip is engaged in the aperture, the said apertured member being formed on the other side with 85 a resilient clip which is adapted to be engaged by the said lever whereby it is held closed to retain the said plate in engaging position.

3. In a clasp of the class described, the combination with an apertured member having guideways along the sides of the aperture and one end thereof looped over to form a resilient clip, a plate having projecting lugs at one end which are adapted 90 to mount it pivotally and slidably in the guideways, a tip adapted to be inserted in the aperture, a lever pivoted on the side of the apertured member opposite the clip having one end bent and having pivotal connection with the other end of the plate, the lever being operative to move the plate in the guideways to clamp the tip in the aperture, the lever being held resiliently when the plate is in clamping position by the clip 95 which engages the bent end of the lever.

4. In a clasp of the class described, the combination with an apertured member having guideways along the inside of the aperture and one end of the member turned over 100 to form a loop and a resilient clip, a second member provided with an enlarged tip separated from the other portion by a neck portion and adapted to be inserted in the aperture, a plate pivotally mounted at one 105 end in the said guideways and longitudinally movable therein, a lever pivotally mounted on the side of the apertured member opposite the clip having one end bent and adapted to engage the clip when the lever is rotated, the said lever being connected intermediate its ends to the free end of the plate to move the plate in the guideway and when rotated to engage the clip 110 and being operative to lock the plate against 115

the neck of the said second member, the free end of the lever being in contact with the enlarged tip thereof.

5. In a clasp, a substantially flat frame having an opening provided with guideways along two opposite edges, a fabric engaging tip for projection through said opening, a plate having one end only confined for sliding and pivotal movement in said guideways into and out of holding engagement with said tip, and means for moving said plate, said means including a lever plate, a pivot for said lever plate fixed with respect to the frame, the lever plate being hinged at a point remote from its pivot to the free end of the first named plate, the first named plate and the lever plate thereby forming a toggle joint construction whereby the first named plate may be moved as specified.

6. In a clasp, the combination with a frame having an opening provided on opposite sides with guideways, of a plate having lugs at one end engaging said guideways to permit sliding and pivotal movement thereof relative to said frame, a member having a fabric engaging tip for projection through said opening, and a lever plate pivoted intermediate its ends to said frame, the pivot point thereof being fixedly located above the frame and guideways, said lever plate also being pivoted to the first named plate to form a toggle joint construction with the one end of the lever plate forming a gripping means to move the toggle construction whereby the first named plate may be moved into or out of holding engagement with the tip when the latter is projected through the frame opening.

40. 7. In a clasp, the combination with a substantially flat frame having an opening provided on two opposite edges with parallel guideways of uniform width throughout their extent, of a plate having lugs at one end engaging said guideways to permit sliding and pivotal movement of the plate relative to said frame, a member having a fabric engaging tip for projection through said opening, and a lever plate fixedly pivoted intermediate its ends to said frame above the guideways and also pivoted to said first named plate, the two plates thereby forming a toggle joint construction with one end of the lever plate as a gripping means to move the toggle construction whereby the first named plate may be moved into and out of holding engagement with the tip when the latter is projected through the frame opening.

55. 8. In a clasp, the combination with a

frame having an opening provided on two opposite sides with guideways, of a plate having lugs at one end engaging said guideways to permit sliding and pivotal movement of said plate relative to said frame, a member having a fabric engaging tip for projection through said frame opening, a lever plate fixedly pivoted intermediate its ends to said frame above said guideways and frame opening and also pivoted intermediate its ends to the free end of said first named plate to form therewith a toggle joint construction having one end of the lever plate as a gripping member to move the toggle construction whereby the first named plate may be moved into and out of holding engagement with said tip when the latter is projected through the frame opening, the remaining end of the lever plate forming a tongue, and a spring for engagement by said tongue when the toggle construction is in the holding position to maintain the hinged members thereof against accidental release.

9. In a clasp, the combination with a frame having an opening provided on two opposite sides with guideways, of a plate having lugs at one end engaging said guideways to permit sliding and pivotal movement of said plate relative to said frame, a member having a fabric engaging tip for projection through said frame opening, a lever plate fixedly pivoted intermediate its ends to said frame above said guideways and frame opening and also pivoted intermediate its ends to the free end of said first named plate to form therewith a toggle joint construction having one end of the lever plate as a gripping member to move the toggle construction whereby the first named plate may be moved into and out of holding engagement with said tip when the latter is projected through the frame opening, the remaining end of the lever plate being formed into a bent tongue to engage and form a stop for the first named plate when the toggle is in the free position, and a spring for engagement by said tongue when the toggle construction is in the holding position to maintain the hinged members thereof against accidental release.

In testimony whereof I have signed my name to this specification, in the presence of two subscribing witnesses, on this 8th day of June A. D. 1911.

ALBERT T. VAN ALSTYN.
